UNITED STATES PATENT OFFICE.

JACOB KAMMERER, OF NEW YORK, N. Y.

WEATHER-STRIP.

968,163.

Specification of Letters Patent. Patented Aug. 23, 1910.

Application filed April 20, 1909. Serial No. 491,007.

To all whom it may concern:

Be it known that I, JACOB KAMMERER, a citizen of the United States, residing at the borough of Manhattan, city of New York, 5 in the county of New York and State of New York, have invented a certain new and useful Improvement in Weather-Strips, of which the following is a specification, reference being had therein to the accompanying drawings, forming part thereof.

My invention relates to weather strips and is particularly adapted for application at the bottoms of casement windows, the sills of which are high and which are not adapted 15 to be used as doors.

The objects of my invention are simplicity and inexpensiveness of construction, durability, prevention of rattling, and a high degree of efficiency in excluding wind, rain 20 and dust.

Other objects and advantages will appear from the following description.

My invention includes a member adapted to be secured to one of two relatively movable parts and provided with a resilient sealing portion adapted to seat in a groove in the other part, such sealing portion being adapted to spring aside to permit the relative transverse movement of the relatively 30 movable parts.

My invention also includes other advantageous features and several details of construction as will hereinafter appear.

I shall now describe my invention with 35 reference to the accompanying drawings and shall thereafter point out my invention in claims.

Figure 1 is a vertical section through the lower rail of the sash and the window sill 40 and through the weather strip. Fig. 2 is a vertical section of the lower rail of the sash. Fig. 3 is a vertical section of the window sill and of the weather strip carried thereby. Fig. 4 is a horizontal section of a casement 45 window embodying my invention, the sash being swung partly open.

In the illustrated embodiment of my invention my improved weather strip is shown as applied at the bottom of the lower sash 50 rail 1 of a swinging sash of a casement window having a window sill 2. The sill 2 is provided with a rabbet 3 at the inner side of the window and has a beveled surface 4 adjacent to the rabbet 3; and the sash rail 1 is 55 provided with a rabbet 5 at the outer side of the window, a concavely rounded groove

6 being formed in the rabbeted face 5 at the inner side of such rabbet. The sash rail 1 is provided at its outer side with a usual drip ledge 7. A sheet metal weather strip 60 is provided and has a plane base portion 8 shown as secured by screws to the top face or meeting face of the window sill 2. The base portion 8 at its inner edge adjacent to the bevel 4 of the sill bends upwardly and 65 inwardly to form a convexly rounded substantially semi-circular sealing rib 9 adapted to seat in and being conformed in shape to the groove 6 in the sash rail 1. The rounded or convexly curved inclined side faces of the 70 rib 9 permit it to yield downwardly when the sash is swung to open position (Fig. 4), while the resiliency of the metal of which the weather strip is formed brings the rib 9 back into sealing relation with the groove 75 6 when the sash is closed (Fig. 1). The outer edge of the rib 9 is prolonged downward to form a flange 10 lying against the vertical face of the rabbet 3. The flange 10 adds to the neatness of appearance of the 80 device when the window is open, but its principal function is to reinforce or strengthen the rib 9 when such rib is subjected to inward and downward pressure by the sash rail 1 in the closing movement of 85 the sash.

In operation, any water which may be blown under the drip ledge 7 and penetrates between the lower rabbeted face of the sash 1 and the upper surface of the base 8 of the 90 weather strip will have its progress arrested and be turned back by the rib 9, rising above the level of the base 1, and also having a close fit in the groove 6 against the surface of which it is pressed by the resiliency or the 95 spring action of such rib. Any shrinking apart of the sash 1 and the sill 2 will be compensated for by the springing upward of the rib 9. The continual close fit of the rib 9 in the groove 6 also precludes the entrance 100 of dust and wind and together with the resiliency of such rib prevents rattling of the sash.

The weather strip is formed of sheet metal, which may be stamped by dies or 105 otherwise bent to the required shape, sheet brass having been found suitable for the purpose.

It is obvious that various modifications may be made in the construction shown and 110 above particularly described within the principle and scope of my invention.

I claim:

1. A weather-tight joint comprising, in combination with two transversely relatively movable parts, one of which is provided with a groove having inclined walls, a sheet metal member having a base secured to the other part and transversely bent to form a resilient rib extending from one edge of the base and adapted to seat in the groove, the rib being provided with inclined sides, the free edge of the rib being extended backward to form a flange extending at an angle to the base, the base-carrying part being provided with a surface extending at substantially the same angle as the said flange and coactive therewith.
2. A weather-tight joint comprising, in combination with the lower sash rail of a

casement window and a window sill having a rabbet formed at the inside of its meeting face, the sash rail having a coacting rabbet formed at the outside of its meeting face and having a groove formed at the inner part of the rabbeted portion, a sheet metal weather strip having a base secured flat against the meeting face of the sill and having a rib adapted to enter the groove in the sash and having a flange extending from the rib into the rabbet of the sill.

In testimony whereof I have affixed my signature in presence of two witnesses.

JACOB KAMMERER.
